STUART PARMELEE MILLER, OF ENGLEWOOD, NEW JERSEY

METHOD AND APPARATUS FOR DISTILLING TAR

Application filed January 18, 1929. Serial No. 332,779.

This invention relates to improvements in the distillation of tar, and includes an improved method of distillation, and improved apparatus therefor. More particularly, the 5 invention relates to an improved method and apparatus for distilling tar by direct contact with highly heated gases, such as coke oven gases, etc.

According to the present invention, tar is 10 distilled and high melting point pitch produced therefrom by direct contact of the tar and pitch with highly heated gases, such as those from coke ovens, gas retorts, etc.; and the hot enriched gases leaving the still are 15 passed through an indirect heat interchanger and condenser for cooling and condensing oils and for preheating tar; and the tar is preheated in this way to a temperature such that part of the light oils are removed there- 20 from and a low melting point pitch is produced. The thus preheated and partly distilled tar is then supplied to the still for further distillation. The present invention is 25 particularly advantageous for the distillation of coal tar at coke oven plants or at coal gas plants by using the highly heated coke oven or coal distillation gases for effecting the distillation.

When tar is distilled by direct contact with 30 highly heated gases, such as coke oven gases, the distillate oils are carried as vapors admixed with the gases leaving the still, and these oils are recovered by subsequent cool- 35 ing of the admixed gases and vapors to effect condensation of the vapors. In order to accom- 40 plish such condensation, it is necessary to cool the gases to their dew point, which is far below their normal condensation tem- 45 perature when free from admixed gases. The complete condensation of lower boiling point oils from admixed gases is difficult, and appreciable loss of such light oils may take place unless the gases are subsequently 50 scrubbed to recover them.

The present invention provides an im- 55 proved process and apparatus in which the light oils are for the most part or completely removed from the tar before it is subjected 60 to distillation by direct contact with the high-

ly heated gases, and in which the highly heated enriched gases from the still are employed for preheating and partly distilling the tar to remove light oils therefrom, and in which the thus preheated and partly distilled tar 55 is then supplied to the still. The lighter oils which are removed by the preliminary pre- 60 heating and partial distillation can be readily condensed because they are free from ad- 65 mixed inert gases. The preheating of the tar by indirect contact with the hot enriched gases from the still serves to cool the gases and condense oils therefrom, thus recovering valuable waste heat and employing it for the 70 preheating and partial distillation of the tar. The removal of the light oils from the tar before it enters the still greatly reduces the 75 loss of light oils with the gases, and greatly improves the condensing operation for con- 80 densing the oils from the inert gases. The condensers can be operated at a higher tem- 85 perature, and the higher boiling oils can be more readily condensed from the gases. The 90 preheated tar thus enters the still in a pre- 95 heated condition where its heat is taken advantage of in increasing the unit distillation capacity of the hot gases in the still.

The present invention is particularly ad- 95 vantageous for distilling tar with fuel gases such as coke oven or gas retort gases, producer 100 gas, water gas, etc. These fuel gases are pro- 105 duced at a high temperature and contain a large amount of waste heat which is com- 110 monly dissipated and lost. Such highly heated 115 gases are produced, for example, at tempera- 120 tures around 550 to 800° C. or higher. They 125 are at such a high temperature that if tar or 130 pitch were brought into contact therewith in limited amounts and with local overheating, 135 the tar or pitch would be rapidly coked. How- 140 ever, by subjecting such gases to thorough and intense spraying with tar or pitch, and by regulating the supply of tar or pitch, 145 the tar or pitch can be rapidly distilled at 150 the same time that the gases are almost in- 155 instantly cooled to a temperature approaching 160 that to which the tar and pitch are heated. In producing high melting point pitch, the 165 gases leave the still highly enriched with oil 170

vapors and at a high temperature. For example, in distilling tar with hot coke oven gases to produce pitch of around 400° F. melting point, the hot enriched gases may 5 leave the still at a temperature around 250 to 400° C., the hot coke oven gases entering the still at a much higher temperature, for example, around 550 to 800° C.

The hot enriched gases from such distillation contain a large amount of heat, partly 10 in the form of sensible heat of the gases and vapors and partly in the form of latent heat of the vapors. According to the present invention these highly heated gases and vapors 15 are utilized for the preheating and partial distillation of tar before the tar is supplied to the still, and the distillate produced by the preliminary preheating and partial distillation is taken off and separately condensed 20 so that only the residue from the preheating and initial distillation enters the still. The preheated and partly distilled tar may enter the still itself or may enter the vapor chamber through which the hot enriched gases leave 25 the still and be there subjected to further distillation before it enters the still proper. In such case, the further distillation will remove additional oils from the tar, but these will be higher boiling oils. These additional 30 oils distilled from the tar by direct contact with the hot gases and vapors will mix with the gases and vapors and be recovered therefrom on subsequent cooling and condensation.

35 The apparatus of the present invention comprises a still connected with a suitable source of highly heated fuel gases, such as those from coke ovens, etc., and having means for bringing the tar and pitch in the still into 40 thorough and intense contact by spraying with the gases passing through the still. The high melting point pitch produced can be drawn off, and the gases and vapors will leave the still as highly heated enriched gases. An indirect condenser is provided for 45 cooling these hot enriched gases and condensing oils therefrom, and this condenser is arranged as a preheater for preheating tar to a temperature to effect partial distillation of 50 it. A separate condenser is provided for the preheated and partly distilled tar, and only the residue from which the distillate has been removed is supplied to the still for further distillation.

55 In addition to preheating and partly distilling tar before supplying it to the still, part of the preheated and partly distilled tar can be drawn off as low melting point pitch, and only the remainder of the low melting 60 point pitch supplied in a preheated state to the still. In this way it is possible to produce simultaneously a high melting point pitch from the still, and a limited amount of low melting point pitch from the preheating 65 operation. This separate withdrawal of part

of the pitch will reduce the amount of pitch supplied to the still, and if the amount so supplied is not sufficient, additional tar, or tar preheated and partly distilled in some other way, can be supplied to the still. In general, however, the process will be so carried out 70 that the preheated tar, from which part of the oil has been removed by the preheating operation, is supplied to the still as the feed of tar or partially distilled tar (pitch), and only such surplus of low melting point pitch will be withdrawn as may be desired for use 75 as a separate low melting point pitch product.

The partial distillation of the tar in the preheater can be supplemented by applying vacuum to the preheater, thus giving an increased percentage of oil distilled from the tar, and a pitch of somewhat higher melting point. The extent to which the distillation is 80 carried in the preheating operation can be regulated to a greater or less extent by regulating the operation of the still and the temperature at which the gases leave it, and the rate at which tar is passed through the preheater. By arranging a generally countercurrent flow 85 of the tar and of the hot gases, the tar can be preheated to a temperature somewhat lower than that of the hot gases leaving the still, and the gases can themselves be cooled to a temperature somewhat higher than that of the cold tar entering the preheater, thus accomplishing more or less free condensation of 90 oils from the hot enriched gases, and preheating of the tar to a temperature such that a considerable percentage of oils will be distilled therefrom.

The indirect condenser and preheater can advantageously be a pipe coil through which the tar is pumped under pressure and around 95 which the hot enriched gases pass in indirect heat interchanging relation with the tar in the pipe coil, and from which it discharges into a vapor box. The tar can be pumped through the pipe coil continuously and under pressure and preferably in a generally countercurrent relation to the hot gases and thereby heated to a high temperature such that when the tar is discharged into the vapor box, a considerable percentage of the tar will be 100 separated in the form of vapors, and a hot pitch of low or medium melting point directly produced. If the vapor box is maintained under a vacuum, the amount of distillate can be considerably increased, and the melting 105 point of the pitch increased, although the temperature of the pitch will be reduced by the further distillation under vacuum.

110 The invention will be further described in connection with the accompanying drawings, which show in a conventional and diagrammatic manner arrangement of apparatus at a coke oven plant embodying the invention and adapted for the practice of the process of the invention, but it is intended 115 and will be understood that the invention is 120 125 130

illustrated thereby but is not limited thereto.

Fig. 1 shows a plan view of a coke oven battery equipped for carrying out this invention;

5 Fig. 2 is an elevation, partly in section, of the tar distilling means shown in Fig. 1;

Fig. 3 is a cross-section on the line 3—3 of Fig. 2;

10 Fig. 4 is a cross-section on the line 4—4 of Fig. 2; and

Fig. 5 shows a slightly modified type of apparatus in elevation.

In the drawings, a coke oven battery 5 is shown equipped with uptake pipes 6, a collector main 7, center box 8, and cross-over main 9 which may be of the usual type and are shown schematically in Fig. 1. At the rear of the coke oven battery of Fig. 1 are additional uptake pipes 10 connected with 15 the hot gas header 11. By manipulation of valves in the uptake pipes 10 connected with the hot gas header and the uptake pipes 6 connecting the same ovens to the usual collector main 7, the gases from these selected 20 ovens may be directed either to the collector main or to the hot gas header.

The hot gas header is heavily insulated as indicated at 12 so that the gases enter the still 13 at only a slightly lower temperature 30 than that at which they leave the ovens. The still is equipped with means for producing an intense spray of tar or partially distilled tar in the gases, so that the tar will be distilled by the hot gases and the hot gases in 35 turn will be detarred by the tar spray. The means shown for producing this spray comprises the roll 14 which is located near the curved wall of the still 15. It is so positioned that it dips to but a slight extent into the tar 40 or pitch within the still. The roll is connected with the motor 16 and when rapidly rotated, e. g. at 900-1200 R. P. M. the roll throws an intense spray of the tar or partially distilled tar from the bottom of the 45 still up into the hot gases passing through the still. The gases enriched in vapors distilled from the tar and almost entirely free from tar fog, leave the still through the tower 17.

The hot enriched gases which may leave 50 the still at a temperature anywhere from 250° C. to 400° C. when medium hard or very hard pitch is being made pass up through the tower 17 and then through the main 18 into the heat interchanger 19 where the hot 55 gases are brought into indirect contact with the tar which is admitted at 20 and passed up through the heat interchanger through the coil 21 in indirect contact with the hot gases and is heated thereby. The gases are 60 cooled by the tar and condensate, which may be a heavy oil or an oil containing a greater or less proportion of light oils depending upon the extent to which the gases are cooled within the heat interchanger, is drawn off 65 into the oil storage tank 22.

The tar which is heated in the heat interchanger and which may leave the heat interchanger at a temperature somewhat lower than the temperature of the gases which enter through the main 18, is conducted through 70 the pipe 23 into the vapor box 24 where vapors of low boiling constituents distilled from the tar separate from the undistilled residue and pass from the vapor box through the vapor main 25 to the condenser 26 which 75 may be of the direct or indirect type. The light oil distillate from this condenser 26 is drawn off into the receiver 27.

The partially distilled tar or low melting point pitch which is left after the distillation 80 is drawn off from the vapor box through the draw-off 28 and may advantageously while still at elevated temperature be fed to the still 13.

The preheated pitch or partially distilled 85 tar from which the low boiling vapors have been removed and collected in the condenser 26, may be fed directly to the still or it may be sprayed into the tower 17 through the sprays 29. If sprayed into the tower 17, this 90

tar or pitch in passing down through the tower will be heated by the hot gases which rise through the tower. This will further preheat and still further distill the tar or pitch before it enters the still. Any portion 95 of the lower boiling constituents of this tar or pitch vaporized in the tower will pass over with the hot enriched gases through the main 18 to the heat interchanger 19. The spray within the settling chamber, which is located preferably between the two sets of baffles 30 and 31, helps to wash from the gases any entrained particles of pitch which may be carried over from the still by the hot 100 gases. The non-volatilized material which collects in the bottom of the tower is preferably admitted to the still at the end at which the hot gases enter the still and is, therefore, advantageously collected in the bottom of the tower and fed to the still 105

110 through the pipe 32. By bringing the partially distilled tar or low melting point pitch from the settling tower into direct contact with the hottest gases and passing the hot gases and the material to be distilled through 115 the still in the same direction, the finished pitch which is preferably of high melting point is sprayed into gases of reduced temperature which are partially saturated with oil vapors and the tendency to coke the high melting point pitch spray is not so great as though the tar and gases flowed countercurrent to one another.

Where the material withdrawn from the vapor box 24 is to be distilled to a point where the greater proportion of the lighter boiling constituents have been removed and is therefore required to be preheated to a relatively high temperature, a higher degree of preheat will result from feeding the resi- 125 130

due from the vapor box directly to the still and preferably at a point in the vicinity of where the pipe 32 enters the still.

The pitch from the still which is preferably a high melting point pitch and may be a pitch with a melting point as high as 400° F. is withdrawn from the still through the trap 33 by means of the adjustable arm 34 and is collected in the trough 35 where it is sprayed with water from 36 and chilled. The chilled pitch and water are collected in the tank 37 and the pitch may be put to any desired use. A pitch of melting point lower than 400° F. may be made e. g. pitch of 180° F. to 200° F. melting point; in such a case the partially or lightly distilled tar from the vapor box may be a less distilled tar than if the higher melting point final pitch were made. Such pitch will preferably not be cooled in water but may be collected in cooling bays or in tanks in which it may be held liquid for subsequent use if desired.

The extent to which the tar is preheated within the heat interchanger 19 and consequently the amount of vapor released in the vapor box may be varied. The production of a pitch of lower melting point may be obtained from the vapor box 24 or a pitch of higher melting point, relatively, may be obtained. Lower boiling constituents are separated from the tar in this vapor box, and since they are not diluted with inert gases, as are the vapors present in the condenser connected with the still 13, these vapors of low boiling constituents may be readily condensed and a high yield of low boiling oils will be obtained directly. Where the quantity of residue drawn off from the vapor box through the draw-off 28 is greater than that which it is desired to add to the still, a portion of this residue may be separately withdrawn through the pipe 38 into the receiver 39 and used for any purpose.

Where the hot enriched gases have been subjected only to partial cooling in the heat interchanger 19, these gases are drawn off into further condensing means 40 which is here shown as a direct condenser in which the gases are sprayed with water or ammonia liquor through the sprays 41. The liquids collecting in the bottom of the condenser 40 are withdrawn to the decanter 42 from which ammonia liquor is separated into the tank 43 and clean oils of relatively low boiling range are collected in tank 44, although it is to be observed that due to the fact that oils of low boiling range have been removed from the tar in the vapor box the quantity of low boiling oils which can be recovered from the enriched gases is less than would otherwise be expected. From the condenser the gases pass to the exhauster 45 and thence to means for the recovery of ammonia and light oils which may be of the usual type. Where it is desired to remove from 24 such a quantity of

partially distilled tar as to leave insufficient for feeding the still 13, or where the amount of tar added at 20 is to be limited, additional tar may be added at 32' or through the line feeding spray 29.

An alternative arrangement is shown in elevation in Fig. 5. The hot gas header 11 and still 13 are of the same general structure as that shown in the preceding drawing, and the settling chamber 17 may be of the same structure, although in Fig. 5 the preheated tar is shown as entering the still at 50 instead of entering the still through the tower 17. The still 13, the header 11, the settling chamber 17, main 18 and heat interchanger 19 are all heavily insulated. The finished pitch from the still is withdrawn through the trap 33 and the hot enriched gases leave the tower 17 through the main 18 and are cooled in the heat interchanger 19. Tar from 20 is passed through the heat interchanger preferably in a direction countercurrent to the flow of the gases and passes in a preheated condition through the insulated pipe 23 to the insulated vapor box 51.

Fig. 5 shows preheating means 19 from which the preheated tar is discharged into a vapor box 51 which is maintained under a vacuum. From the vapor box the vapors pass to a condenser 52 which is also maintained under vacuum. A vacuum pump 53 is shown at 23. It is connected with the condenser 52. The clean low boiling oils condensed from the vapors which are separated from undistilled residue in the vapor box and which, because of the vacuum, may comprise oils of higher boiling range than would ordinarily be produced in the vapor box, are withdrawn through the separator 53' and the barometric column 55 and collected in the clean oil storage 56.

The undistilled residue from the vapor box is withdrawn through a similar barometric column 57 and collects in the receiver 58. Residue from this receiver is pumped in preheated condition by the pump 59 through the insulated line 60 into the still 13 at 50. A portion of the undistilled residue may be withdrawn through the line 61 into the low melting pitch storage tank 62 and be employed for any desired purpose. Where withdrawal of the greater proportion of such partially distilled tar is desired, additional tar may be introduced through 50' for production of hard pitch in still 13.

The gases leaving the heat interchanger 19 through the main 63 may contain some oil vapors carried over from the still by the gases through the main 18 which are not condensed in the heat interchanger 19. This will be true when the condensation is so regulated as to collect only the heavier oils in the clean oil storage 22. Since the tar is "topped" in the vacuum vapor box 51 before being admitted to the still 13, the content of vapors

of low boiling oils in the enriched gases will be low. Any oils leaving the heat interchanger 19 through the main 63 may be condensed in further cooling apparatus for recovery of uncondensed oil and the gases will then be treated as usual for the recovery of ammonia and the usual light oils.

I claim:

1. The method of distilling coal tar by direct contact with highly heated coke oven gases, which comprises distilling pitch by spraying it into the gases in a still with such thoroughness and intensity that the gases are rapidly cooled to a temperature approximating that to which the resulting pitch is heated, regulating the operation so as to produce a high melting point pitch and hot enriched gases leaving the still, passing the hot enriched gases in indirect contact with the coal tar to preheat the tar, regulating the rate of supply of the tar to the preheater so as to preheat it to a temperature sufficient to effect partial distillation thereof, separating the resulting vapors of lower boiling point oils from the preheated and partially distilled tar residue, withdrawing the distillate from such partial distillation, and supplying the tar residue to the still in the form of low melting point pitch to be there further distilled to produce high melting point pitch, whereby the distillate produced in the still by direct contact with the hot coke oven gases is a distillate relatively free from low boiling point oils, which can be readily condensed from admixture with the gases on cooling.
2. The method of distilling coal tar by direct contact with highly heated fuel gases, which comprises bringing such gases into direct and intimate contact with a spray of pitch in a still whereby the pitch is distilled and regulating the intensity of the spray and the operation of the still to produce high melting point pitch and hot enriched gases leaving the still, passing the hot enriched gases into direct contact with preheated and partly distilled tar to effect further distillation thereof, passing the resulting hot enriched gases into indirect heat interchanging relation with the coal tar to be preheated and distilled and thereby cooling the enriched gases and condensing oils therefrom, regulating the supply of tar to the indirect preheater so that it will be preheated to a temperature that will effect partial distillation of oils therefrom, separating the resulting oil vapors from the preheated and partially distilled tar residue, separately withdrawing and condensing the oils so distilled, passing the tar residue into direct contact with the hot enriched gases leaving the still and thereby effecting further distillation of oils therefrom and further preheating of the residue, and supplying the resulting preheated and partly distilled residue to the still for further distillation therein.

3. The method of distilling coal tar and of simultaneously producing high melting point pitch and low melting point pitch which comprises subjecting preheated and partially distilled tar (pitch) to distillation by direct contact with highly heated fuel gases in a still and regulating such distillation to produce high melting point pitch and hot enriched gases, passing the hot enriched gases

into indirect contact with the coal tar to be preheated, thereby cooling the gases and condensing oils therefrom, and preheating the tar, regulating the supply of tar to the preheater so that it will be heated to a temperature sufficient to distill part of the oils therefrom, withdrawing the preheated tar into a vapor separating chamber and separately condensing the resulting distillate, withdrawing low melting pitch residue remaining from such preheating and distillation, and supplying part of such low melting point pitch residue to the still to be there further distilled to produce high melting point pitch.

4. The method of distilling coal tar by direct contact with highly heated coal distillation gases which comprises distilling tar or pitch by bringing tar or pitch in a still into thorough and intimate contact with the gases in a still under such regulated conditions that a high melting point pitch residue is produced and highly enriched hot gases leave the still, passing the hot enriched gases through a heat interchanger and indirect condenser into indirect heat exchange relation with tar to be preheated and distilled, regulating the flow of tar through the interchanger and condenser to effect preheating of it to a temperature sufficient to distill part of the oils therefrom when subjected to reduced pressure, subjecting the preheated tar to such reduced pressure thereby effecting such distillation, drawing off and separately condensing the oils so distilled, and supplying at least part of the preheated and partly distilled tar to the still.

5. An apparatus for distilling tar, comprising a still provided with means for introducing highly heated gases therein and for spraying pitch into the gases to effect its distillation so that high melting point pitch can be produced and hot enriched gases leave the still, a heat interchanger and indirect condenser, means for passing the hot enriched gases from the still to the interchanger and condenser to effect cooling thereof and condensation of oils therefrom, means for supplying tar to be preheated to the interchanger and condenser to effect its preheating and partial distillation, means for withdrawing and separately condensing the distillate so produced, and means for supplying the partly distilled tar, freed from such distillate, to the still to be there further distilled to produce high melting point pitch.

6. An apparatus for the distillation of tar,

- comprising a still provided with means for introducing fuel gas thereto in a highly heated state and with means for bringing pitch into intimate contact with the gases in the still, means for withdrawing high melting point pitch from the still, means for withdrawing hot enriched gases from the still and for passing them into indirect heat exchange relation with tar to be preheated and partly distilled, means for drawing off the condensate from such indirect preheater, means for supplying tar in a regulated way to said preheater, means for drawing off and separately condensing the distillate produced by such preliminary distillation, means for introducing preheated residue from such preliminary distillation into direct contact with the hot enriched gases leaving the still to effect further preheating and distillation thereof, and means for introducing the resulting preheated and partially distilled residue into the still to be there further distilled. 7. An apparatus for distilling tar, comprising a still having means for introducing highly heated fuel gases thereto and for withdrawing hot enriched gases therefrom, means for bringing pitch in said still into intimate and thorough contact with the gases passing therethrough whereby high melting point pitch can be produced and hot enriched gases leaving the still, a heat interchanger and indirect condenser and tar preheater having pipe coils therein over which the hot enriched gases pass to effect preheating thereof and cooling of the gases and condensation of oils therefrom, means for supplying tar to said pipe coils to preheat it by indirect contact with the hot enriched gases, a vapor box into which said pipe coils discharge, a separate condenser arranged to condense the vapors removed in said vapor box, and means for introducing the preheated residue from said preheating and partial distilling operation into the still for further distillation. 8. An apparatus for distilling tar comprising a still provided with means for introducing highly heated gases therein and for spraying pitch into the gases to effect its distillation so that high melting point pitch can be produced and hot enriched gases leave the still, a heat interchanger and indirect condenser, means for passing the hot enriched gases from the still to the interchanger and condenser to effect cooling thereof, and condensation of oils therefrom, means for supplying tar to be preheated to the interchanger and condenser, means for withdrawing the preheated tar therefrom, and a vacuum pump with means for subjecting the preheated tar to reduced pressure, means for withdrawing and separately condensing the distillate produced under reduced pressure, and means for supplying the partly distilled tar free from such distillate to the still to be there further distilled to produce high melting point pitch. In testimony whereof I affix my signature.
